CLAIM

The ornamental design for an open compression-type coaxial cable connector, as shown and described.

DESCRIPTION

FIG. 1 is a perspective view of an open compression-type coaxial cable connector according to the present invention; FIG. 2 is a side view thereof, all other side views being a mirror image thereof; FIG. 3 is a bottom view thereof; and, FIG. 4 is a top view thereof.

As is illustrated by the broken lines in FIGS. 1 and 2, applicant is not presently claiming the indentation on the outer component. As is illustrated by the broken lines in FIGS. 1 and 2, applicant is also not presently claiming any surface configuration or ornamentation for the inner component that accepts the outer component. Finally, as illustrated by FIGS. 3 and 4, applicant is also not presently claiming any features of the inside of the connector as viewable from the bottom or top views of the connector.
